United States Patent Office.

A. B. GREENWALT, OF BALTIMORE, MARYLAND.

Letters Patent No. 60,882, dated January 1, 1867.

IMPROVEMENT IN TATTING SHUTTLES.

The Schedule referred to in these Letters Patent and making part of the same.

TO ALL WHOM IT MAY CONCERN:

Be it known that I, A. B. GREENWALT, of Baltimore, in the county of Baltimore, and State of Maryland, have invented a new and improved Tatting Shuttle; and I do hereby declare the following to be a full, clear, and exact description of the same, sufficient to enable one skilled in the art to which the invention appertains to make use of it, reference being had to the accompanying drawing, which forms a part of this specification, in which—

Figure 1 is a central longitudinal section.

Figure 2 is an elevation.

This shuttle is provided with a pin which can be projected when it is required to pass a thread through a loop to fasten one section of the tatting to another, a spring withdrawing the pin when not in use. It is usual to keep a pin in the bosom of the dress when tatting, as it is frequently though only occasionally required, the greater part of the work consisting of a succession of knots each made by passing the shuttle through a loop; but ornamental tatting is not a merely continuous string of knots, but is united at various points by knotting into loops which are left occasionally for that purpose, the work being made to assume the form of rosettes, leaves, scrolls, fret-work, &c., &c., according to the taste and leisure of the person.

In the drawing, the shuttle is shown made with cheeks *aa*, and a central spool upon which the thread is wound; *b* is a needle or sharp-pointed pin, which is retracted into the sheath *C*, by the spring *d*, but may, by pressure upon the stud *e*, be made to project as shown in red lines, in which position it is useful for the purpose described of picking the thread through the loop in the manner familiar to those acquainted with the operation. Thus the pin is kept constantly in readiness for use by a simple motion of the thumb or finger which propels it from its case.

Having described my invention, what I claim therein as new, and desire to secure by Letters Patent, is—

The tatting shuttle as an article of manufacture provided with a pin, thumb-knob, and retracting spring, substantially as described.

A. B. GREENWALT.
